UNITED STATES PATENT OFFICE.

HANS SENGBUSCH AND JOHN ERICKSON, OF CHICAGO, ILLINOIS, ASSIGNEES, BY
MESNE ASSIGNMENTS, TO AUTOMATIC ELECTRIC INC., OF CHICAGO, ILLINOIS, A
CORPORATION OF DELAWARE.

ELECTROMAGNETIC DEVICE.

Application filed April 25, 1924. Serial No. 708,870.

The present invention relates in general to electromagnetic devices, but is particularly concerned with devices of the type in which it is necessary to adjustably position the electromagnets on their supporting frame; and the particular object of the invention in the present instance is to provide an improved method of adjustably supporting the electromagnets of such a device, which is decidedly preferable to any method heretofore known.

The well known Strowger switch is a good example of an electromagnetic device which is provided with the so called vertical and rotary magnets which are adjustably secured to the supporting frame to enable the distance between the magnets and their armature to be adjusted.

In order to describe the invention the same has been illustrated in a drawing comprising Figs. 1 and 2.

Fig. 1 is an enlarged plan view of the parts used to adjustably secure an electromagnet to its supporting frame in accordance with the invention.

Fig. 2 shows an enlarged view of the invention as applied to a pair of vertical or rotary magnets of an ordinary Strowger switch. In this figure certain of the parts are shown in cross section in order to make clear the relation between various parts.

In Fig. 1 of the drawings the adjusting screw 1 and the holding screw 3 are the same as those used heretofore for adjustably securing the magnets to the switch frame, while the socket wrench member 2 comprises the means which, when used in conjunction with members 1 and 3, constitutes the means for adjustably securing a magnet to the switch frame in accordance with the present invention.

In Fig. 2, by disregarding the member 2, we have illustrated the old method by which the above results are accomplished. When securing a magnet to the frame, according to the old method, the adjusting screw 1 is screwed into place in the frame 4, and the holding screw 3 is dropped down through the opening in adjusting screw 1 and through a hole in the usual yoke member 5. The screw 3 is then screwed into a threaded opening in the core 6 of the magnet 7 until the core 6 and member 5 are drawn up against adjusting screw 1. If it proves nec-

essary to shift the magnet either away from or nearer to its armature the screw 3 is slightly loosened and the adjusting screw 1 turned to the right or left, depending, of course, upon which adjustment is desired, and the screw 3 is then again tightened down against adjusting screw 1, the operation of loosening screw 3 and turning adjusting screw 1 to the right or left and then again tightening screw 3 being repeated until proper adjustment is made.

The above method of adjustably securing the magnet to the frame is very satisfactory so long as a tight fit is obtained between the threads of the adjusting screw and the threads of the frame. In quantity production, however, it is difficult to maintain a uniformly tight fit between these parts, due to the wear on, and frequent breakage of, the jigs, taps, and dies used in their manufacture. As a result, unless a close inspection is continuously carried on, certain of the adjusting screws will fit loosely in the frames and in this case, no matter how tightly adjusting screw 1, yoke 5, and core 6 are held together by holding screw 3, play will still exist between the core 6 of magnet 7 and frame 4. When this condition exists proper operation of the magnet is impossible, and the only thing to do is to replace the adjusting screw with a slightly larger one.

On the other hand, in certain instances the adjusting screws 1 prove to be such a tight fit in the frame that it is almost impossible to turn them and they are quite often broken. In these instances much time is wasted in removing the adjusting screws and replacing them with new ones.

In the present case all these various troubles are overcome by adding the socket member 2. The various parts are secured to the frame in the same manner as formerly, but with the addition of member 2 placed over adjusting screw 1. Adjusting of the magnet is accomplished the same as heretofore with the exception that adjusting screw 1 is rotated in either direction through the medium of socket member 2. In tightening up the screw 3, however, the tension exerted between the head of the holding screw and the core of the magnet not only draws the core 6, yoke 5, and adjusting member 1 tightly together as in the former case, but

in addition, since the head of screw 3 is now supported by socket member 2, which in turn is supported by the supporting frame, any play existing between the threads of adjusting screw 1 and the threads of the frame 4 is taken up. Therefore, no close fit between the threads of adjusting screw 1 and the frame 4 is necessary.

Since no close fit is necessary between 10 these members the adjusting of the magnet is made relatively easy and at the same time any danger of having loose magnets due to play in the threads between the frame and the adjusting screw is overcome in a highly 15 satisfactory manner.

While the invention is illustrated as using a yoke member 5 between the adjusting screw 1 and the core 6, it should be understood that this has nothing to do whatever 20 with the invention, but is merely shown in conformance with the usual practice in the construction of the Strowger type switches referred to.

What is claimed is:

25 1. In an electro-magnetic device, a frame, a magnet associated therewith, a tubular adjusting screw loosely fixed to said frame for adjusting the distance between said magnet and said frame, and means jointly effective 30 for holding said adjusting screw in tight fixed relation to said frame and for holding said magnet in fixed relation to said adjusting screw.

2. In combination, a magnet core, a frame 35 having a threaded opening therein, a tubular adjusting screw extending through said opening on both sides of the frame for spacing said core therefrom, a perforated auxiliary adjusting member enclosing the 40 head of said adjusting screw and resting against the said frame, a threaded opening in one end of said magnet core in line with the opening in said tubular adjusting screw, and a clamping screw extending through the 45 said auxiliary member and adjusting screw and entering the threaded opening in said core to secure the parts together.

3. In an electro-magnetic device, a frame

a magnet, an adjustable mounting means comprising a tubular adjusting screw 51 threaded into the frame on which the device is mounted, a perforated collar fitted over the head of said adjusting screw and resting against said frame, a threaded opening in the device to be mounted, a machine screw 51 extending through said collar and adjusting screw into said opening, said collar and adjusting screw cooperating to position said device with respect to said frame and said collar, machine screw and device cooperating to lock said adjusting screw in place.

4. In an electro-magnetic device, a magnet, a frame for supporting said magnet, a polygonally headed adjusting screw for varying the distance between the core of 61 said magnet and said frame, a polygonally shaped member encompassing the head of said screw permitting endwise movement of the screw therein and resting against the frame, and a retaining screw passing 70 through the member and collar into the core of the magnet, said screw when tightened, clamping the magnet against the members at any distance from the frame and clamping the members into the frame.

5. In an electro-magnetic device, a magnet, a frame for supporting said magnet, and adjusting screw extending through the frame and movable thereto to space the magnet at various distances from the frame, a 80 collar telescoped over the head of the adjusting screw and bearing against the frame on the opposite side from the magnet, each rotary movement of the collar causing an 85 endwise movement of the adjusting screw, and a locking screw holding the magnet against the adjusting screw and holding the adjusting screw in fixed relation to the frame.

In witness whereof, I hereunto subscribe 90 my name this 22d day of April, A. D., 1924.

HANS SENGBUSCH.

In witness whereof, I hereunto subscribe 95 my name this 22 day of April, A. D., 1924.

JOHN ERICKSON.
